CARTRIDGE MAGAZINE

Reginald F. Sedgley and Martin Wurzer,
Philadelphia, Pa.

Application June 9, 1933, Serial No. 675,030

11 Claims. (Cl. 42—50)

The object of our invention is to devise a novel construction and arrangement of a cartridge magazine wherein the cartridges are automatically fed to the discharge opening.

5 Our present invention, although not limited to such use, is especially adapted for use with rim fire .22 calibre cartridges.

In the cartridge magazines of the rotary type as heretofore employed with machine guns, no provision has been made for feeding rim fire cartridges and due to the extension caused by the annular flange of the rim they have not been accurately fed and there has always been the liability of the magazine becoming inoperative 15 due to the clogging of the cartridges in their feed channel.

In accordance with our present invention, we employ a cartridge carrying rotor, and provide positive means for advancing a cartridge into the discharge opening in such a manner that its rim is in advance of the rim of a juxtaposed cartridge, so that the cartridges brought into discharge position will be in proper alignment with the bore of the gun.

25 A further object of the invention is to devise an automatic rotary cartridge magazine which will consist of a minimum number of parts; which can be locked in loading position and which can be loaded in a minimum of time and by an unskilled person.

With the above and other objects in view as will be hereinafter more clearly set forth, our invention comprehends a novel cartridge magazine of the rotary type.

35 It further comprehends a novel cartridge magazine having a novel casing, a novel cartridge carrying rotor, and novel means for effecting the progressive feed of the cartridges to the discharge of the magazine.

40 It further comprehends novel means for locking the rotor against rotation, and for releasing it.

Other novel features of construction and advantage will hereinafter appear in the detailed description and the appended claims.

45 For the purpose of illustrating our invention, we have shown in the accompanying drawing a preferred embodiment of it, which, in practice, will give satisfactory and reliable results. It is, however, to be understood that this embodiment is typical only, and the various instrumentalities of which our invention consists can be variously arranged and organized, and the invention is not limited to the exact arrangement and organization 50 of these instrumentalities as herein set forth.

Figure 1 is a side elevation of a cartridge magazine embodying our invention.

Figure 2 is a section on line 2—2 of Figure 1. Figure 3 is a sectional detail of the rotor handle.

5 Figure 4 is a detail view showing more clearly the manner in which cartridges pass from the rotor to the delivery opening.

Figure 5 is an exploded view of certain of the parts.

10 Figure 6 is a sectional detail showing more particularly the manner in which the cartridges are fed.

Figure 7 is a top plan view of a ramp, in detached position.

15 Similar numerals indicate corresponding parts. Referring to the drawing:

The cartridge magazine is provided with a sectional casing consisting of the body portion 1 and the lid or cover 2 which has a frictional fit 20 with the body portion. The body portion is provided in its periphery with a cartridge delivery opening 3, to which the cartridges are progressively fed by a rotor 4. The rotor 4 has at its periphery individual means to receive and carry 25 the cartridges, and, as illustrated, outwardly projecting arms 5 are provided with rounded bottoms and adapted to form pockets 6 to receive the cartridges. The feed of the rotor is caused by a spring 7 coiled around an inwardly extended 30 annular flange 8 of a disc 9. The flange has a driving fit with the walls of the central opening 10 of the body portion 1, so that it is in fixed relation therewith. One end of the spring is fixed 35 to the rotor as at 11 and the opposite end is fixed to the flange 8 as at 12, the spring being confined in the channel formed between such flange and the rotor.

The disc 9 has fixed to it one end of a locking member 13 in the form of a flat spring, the free end of which is adapted to enter a slot 14 in the rotor when the latter has been rotated into loading position by a telescopic handle 15, one tubular section of which is carried in one of the pockets of the rotor and is of the same diameter 45 and contour as that of the shell of one of the cartridges 16. 17 is the grasping member of the handle which is concealed within the casing when the cover is on the body portion.

The cover is provided with a releasing member 50 18 in the form of a pin adapted when the cover is in place and the rotor loaded to move the locking spring 13 out of the slot 14 in the rotor.

As a cartridge is fed to the delivery opening 55 by the rotor it comes into the path of a ramp

19 secured to the body portion, thereby moving the cartridge rearwardly and after the cartridge passes through the delivery opening its rim or butt engages the cam 20 to cause the cartridge to move forwardly into a cartridge holder 21 formed by spring clips secured to the body portion. 22 designates a cartridge pick up in the form of a curved plate extending downwardly through the delivery opening into the path of the cartridges on the rotor so that they will be guided upwardly through the delivery opening. The ramp 19 has an upwardly extending arm 23 which is recessed to form a seat for the forward end of the cartridge when it is in the cartridge holder. Two pairs of spring clips are employed to form the cartridge holder 21 and between such pairs are the cam plates 24 which cause the cartridge to be properly aligned with the bore of the gun as it is being ejected from the cartridge holder.

20 Assuming now that it is desired to load the cartridge holder, the cover is removed, rendering the handle 17 accessible. The operator now rotates the rotor 4 in a counter clock-wise direction until the locking spring 13 enters the slot or recess 14 of the rotor. The rotor is now stationary and the operator has both hands free to load cartridges into the individual cartridge receiving pockets of the rotor. After the rotor is loaded, the cover is replaced and the spring release 18 forces the locking spring 13 out of the slot 14 of the rotor, so that the spring 7 is now free to feed the rotor.

35 The casing is provided with any desired or conventional means for aligning it with the machine gun or rifle with which it is used, such as for example, the slotted bracket 25 secured to the side wall of the body portion of the casing.

40 When the cartridge is moved forwardly in the holder the seat 23 serves as a ramp to tilt the forward end of the cartridge upwardly so that it will enter the bore of the gun.

45 Our present invention is particularly adapted for the feeding of rim fire .22 calibre cartridges having an outwardly extending annular flange at its butt end. The ramp 19 and cam 20 cause the cartridge in the cartridge holder to have its butt or rim in advance of that of the cartridge beneath it, which is the next cartridge to be fed, and thus prevents any clogging of the magazine 50 and interruption in its feed.

The rotor has an annular channel at its periphery into which the cartridge pick up extends.

55 As will be apparent the magazine may be made in different sizes to provide any desired capacity of cartridges.

The cover or lid preferably has a central opening 26 of the same diameter as the opening 10 in the body portion of the casing.

60 It will now be apparent that we have devised a new and useful cartridge magazine which embodies the features of advantage enumerated as desirable in the statement of the invention and the above description, and while we have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described our invention what we claim as new and desire to secure by Letters Patent, is:

75 1. A cartridge magazine, comprising a casing having a cartridge delivery opening, a rotor hav-

ing individual cartridge receiving means at its periphery, means to cause a rearward movement of the cartridge as it is fed towards said opening, means to cause a cartridge in registry with said opening to pass through it, and means to effect a forward movement of a cartridge after it has passed through said opening.

5

2. A cartridge magazine comprising a sectional casing having an unobstructed central opening, one section of which has a delivery opening, a spring actuated rotor in said casing and having individual cartridge retainers at its periphery, means to cause cartridges to progressively pass from said rotor through said delivery opening, a holder, on a casing section to receive a cartridge and a ramp on the casing at the discharge end of said holder to tilt upwardly the forward end of a cartridge as it is being fed from the holder.

3. A cartridge magazine, comprising a sectional casing, one section of which has a delivery opening, a spring actuated rotor having individual cartridge retaining means at its periphery, a cartridge pick up to remove a cartridge from said rotor and guide it to said delivery opening, a ramp to cause rearward longitudinal movement of a cartridge being fed to said opening, a cartridge holder exterior of said opening, and means to cause a forward longitudinal travel of a cartridge passing into said holder, so that its rim or base will be in advance of the next cartridge fed to said holder.

4. A cartridge magazine, comprising a casing having a delivery opening, a rotor having non-radial individual cartridge retaining means at its periphery, a cartridge pick up to remove a cartridge from said rotor and guide it to said opening, a cartridge holder in the form of a pair of clips to which a cartridge passes from said delivery opening, and means to advance a cartridge passing to said clips so that its base or rim is in advance of the next cartridge to be fed from said rotor.

35

5. A cartridge magazine, comprising a casing having a delivery opening and provided with a removable cover, a cartridge holder to receive a cartridge from said opening, a cartridge pick up to remove a cartridge from said rotor and guide it to said opening, a catch to lock said rotor against rotation, and means carried by said cover to release said catch when said cover is in position on the casing.

45

6. A cartridge magazine, comprising a casing having a delivery opening, means to feed cartridges to said delivery opening, clips on the casing to receive cartridges from said delivery opening, and means to cause a cartridge in said clips to have its base or rim in advance of the next cartridge being fed to said clips.

55

7. A cartridge magazine, comprising a sectional casing having a delivery opening, a spring actuated rotor having individual cartridge retaining non-radial pockets at its periphery, a handle in one of said pockets to rotate said rotor to tension the spring, a locking member to hold said rotor in loading position, means carried by a casing section to release said lock, and means for causing said cartridge to pass from said rotor to said delivery opening.

60

8. A cartridge magazine, comprising a casing having a delivery opening, and a cover, a spring actuated rotor having non-radial cartridge receiving pockets at its periphery, means to cause a cartridge to pass from its pocket to said opening and a collapsible handle in one of said pockets to rotate the rotor to tension its spring, said

65

70

75

handle being concealed when the cover is closed and accessible for use when the cover is open.

9. A cartridge magazine, comprising a casing having an unobstructed central opening and a delivery opening at its periphery, clips to receive a cartridge from said opening, a spring actuated rotor in the casing having non-radial cartridge receiving pockets, a ramp on the casing to cause a cartridge to pass from its pocket to said opening, and a second ramp on the casing to cause longitudinal advancement of said cartridge as it passes from said opening into said clips.

10. A cartridge magazine comprising a sectional casing having a peripheral discharge opening, a spring actuated rotor in said casing having pockets in its periphery to receive individual cartridges, a cartridge holder on the casing to receive cartridges from said rotor, a ramp on the

casing to guide cartridges to said opening, and a ramp on the casing at the discharge end of said holder to tilt upwardly the forward end of a cartridge being fed from said holder.

11. A cartridge magazine, comprising a sectional casing having a peripheral discharge opening, a rotor in said casing having peripheral pockets to receive individual cartridges, clips at opposite sides of said opening to retain a cartridge, means on said casing to cause longitudinal movement of a cartridge passing to said opening, a ramp on the casing to cause a cartridge being fed by the rotor to pass to said delivery opening, and a ramp on said casing to cause upward tilting of the forward end of a cartridge being fed from said holder.
